UNITED STATES PATENT OFFICE.

PAUL GNIFKE, OF MILWAUKEE, WISCONSIN, ASSIGNOR TO RAILWAY ELECTRIC
MANUFACTURING CO., OF MILWAUKEE, WISCONSIN.

SELECTOR.

1,413,329.

Specification of Letters Patent. Patented Apr. 18, 1922.

Application filed July 16, 1917. Serial No. 180,708.

To all whom it may concern:

Be it known that I, PAUL GNIFKE, a subject of the Emperor of Germany, residing at Milwaukee, in the county of Milwaukee and State of Wisconsin, have invented a certain new and useful Improvement in Selectors, of which the following is a full, clear, concise, and exact description, reference being had to the accompanying drawings, forming a part of this specification.

My invention relates to selectors and more particularly to the type of selectors known as a step-by step selector, and concerns itself particularly with the provision of a selector of this nature for substation work. The selector of my invention is adapted for use in connection with a plurality of similar selectors on a signal circuit, means being provided at a central station to selectively actuate any predetermined one of the selectors associated with the line.

In my co-pending application Serial No. 180,707 filed July 16, 1917, on which Patent No. 1,309,569 was issued July 8, 1919; I set forth a central station signal sending device which is of use in connection with the selector herein disclosed.

My invention herein is an improvement over the selector disclosed in the patent to Burnett No. 1,110,418, issued September 15, 1914.

My improved modified selector has provision whereby all of the other stations on a party line may be locked out so that the party called may use the line exclusively for telephonic or similar purposes. The selector herein is in general of the type operable by impulses of opposite polarity which style of operating current is herein referred to as alternating current.

In order to carry out my invention, I arrange the substation selectors in such a way that more than one impulse of the alternating current intervenes between each succeeding station. Thus if it requires two alternations or one cycle to call the station No. 1, then the system will be so arranged that it would require two additional alternations to call station No. 2. There is thus an intermediate position of the step by step element, namely that due to the sending of one additional impulse or alternation which can be used to advantage, and this is utilized for

lock out purposes. Thus, if it is desired to call station No. 4, for instance, and lock out all of the remaining stations, then in accordance with the above discussion four cycles of alternating current are transmitted to the line whereby the signal at station No. 4 is operated. If one additional alternation (not cycle) of alternating current is transmitted to the line, this additional impulse will not be sufficient to have the selector at station No. 5 respond as it requires one complete cycle to bring the selector at the next following station into operative position, as before stated. Thus this additional impulse or alternation sets the selector at the called station into such a condition that that particular station has its telephone or other substation equipment connected to the line, whereas the intermediate positions occupied by the selectors at the remaining stations prevent connection of their substation equipments to the line. If, on the contrary, it is desired to have all of the substation equipments connected to the line, then the calling device after having been operated to transmit a call for a predetermined station is continued in its operation so that the step by step elements at the selectors complete their cycle of movement to their starting position, at which time all of the substation talking or similar equipments are connected to the line, it being remembered however that the predetermined station only has its signaling device actuated.

What has been said with regard to alternations in the above paragraph is equally true if instead of "alternations" of current, "cycles" of current are used as the units of calculation.

In the particular form of my invention herein I have assumed that two cycles shall intervene between succeeding stations; thus that it requires two cycles of alternating current to send a call for station No. 1, four cycles for station No. 2, and so on. I then use for the locking out impulses one complete cycle of alternating current, which under these circumstances is not sufficient to step up to signaling position the selector at the station succeeding the one which has been called. This one cycle of alternating current can thus be used for the lock out purposes, as previously explained.

I will explain my invention more in detail by referring to the accompanying drawings, in which—

Fig. 1 is a front view of a selector constructed in accordance with my invention;

Fig. 2 is a sectional view on line 2—2 of Fig. 1;

Figs. 3, 4, 5 and 6 are fragmentary views of the control mechanism of the selector;

Figs. 7, 8 and 9 are fragmentary views of the three different positions occupied by the circuit controlling elements which control the substation circuits;

Fig. 10 is a diagrammatic view illustrating the circuit connections involved, and

Fig. 11 is a fragmentary top view of a part of the step by step mechanism.

My improved selector is mounted on a base board 10 to which is secured the permanent magnet 11 through the agency of the screws 12. This permanent magnet through the agency of the screws 13 supports the remaining selector equipment. This selector equipment consists of the two actuating coils 14 and 15 preferably connected in series which are mounted upon cores 16, 17 respectively, these cores being secured to the heel piece 18 through the agency of the screws 19, 19. The heel piece 18 in turn is held by the screws 13 to the permanent magnet, as already explained. The pole pieces 20 and 21 project below and are in close proximity to an oscillatingly mounted armature 22, which armature is pivotally supported at 23 and 24, as clearly apparent. The pole pieces also have inwardly projecting extensions 25 and 26 in co-operative relation with the armature 27, this armature being removably carried by the swinging element 28 pivoted at 29. The armature 22 is polarized due to the extension 30 extending forwardly from the permanent magnet 11, but the armature 27 is not polarized and hence is attracted and swung counter-clockwise from the position it occupies in Fig. 2 whenever current is present in the coils 14, 15. The armature 22 being polarized oscillates back and forth due to the changes of the alternations when alternating current is impressed on the coils 14, 15. The alternating current when passing through the coils 14, 15 causes the armature 27 to be attracted between the extensions 25 and 26 and to remain there during the continuance of this current. The armature together with its element 28 is sluggish enough so that it will not be restored during the small time interval that intervenes between alternations or impulses, if there is any. The magnetic circuit which includes the cores 16, 17, divides and takes two paths at the lower extremity of these cores, as will be readily understood from what has been thus described. The armature 27 cannot move further than into a position where its

right hand toe hits the standard 31. This standard 31 forms part of a bridge structure 32, which bridge structure is secured to the extensions 25 and 26 intermediate of the pole pieces 20 and 21. This bridge structure 32 extends forwardly, as more clearly apparent from Fig. 2, and consists of non-magnetic material. Besides supporting the armatures 22 and 27 at the points 23, 24 and 29, respectively, this bridge also carries all of the rest of the equipment, which operates with these two armatures. The element 28 is likewise of non-magnetic material, and so is its upper extension 33. A shaft 34 mounted between the standards 31 and 35 supports the rotatable step by step apparatus of the selector. It may be stated that the bridge structure 32 consists of two plates held together by the bolts 36, 36. The shaft 34 fixedly carries the escapement wheel 37 which is acted upon by the escapement 38 so that this escapement wheel 37 moves one position with each movement of the armature 22. The escapement 38 is pivotally carried by a stud 39 and carries at its lower extremity a pair of fingers 40 which co-operate with a pin 41, this pin being carried by an upwardly extending arm 42 rigidly secured to the armature 22. This upwardly extending arm terminates in a finger 43. The element 28 likewise has a forwardly projecting finger 44. The element 28 also has a forwardly extending toe 45. Upon the same shaft 34 which carries the escapement wheel 37 there is mounted a disc 46, this disc having a notch 47, which notch has a different angular position relative to the disc 49 at each one of the selectors connected to the same line. This provides a different operative position for each one of the selectors on the line so that the selectors are selectively responsive to different numbers of impulses or alternations. Immediately adjoining the slot 47 and rearwardly thereof relative to its direction of operative rotation there is provided the projection 48 which is used for lock out purposes as will presently appear. This disc 46 may be adjusted relatively to the shaft 34 so as to accommodate the selector for any desired number of impulses, the engagement between these parts being frictional. After the disc 46 has once been set for a particular station it remains there unless it is desired to change the combination or number of impulses required to actually operate that particular selector. Fixedly secured to the shaft 34 is the disc 49. This disc has various projecting fingers which accomplish the same functions as outlined in the patent to Burnett above mentioned. These fingers are respectively the fingers 50, 51 and 52. A flexible conductor 53 extends to the element 28. This element 28 carries two contacts, respectively the con-

tacts 54 and 55. These contacts respectively co-operate with fixedly mounted contact springs 56 and 57.

The normal position of the selector is indicated by the parts as shown in Fig. 3. If impulses are received by the coils 14 and 15 the armature 27 is immediately attracted and held in its attracted position. These alternating impulses oscillate the armature 22, which thereupon operates the escapement 38 to step up the escapement wheel 37 a number of steps equivalent to the number of alternations or impulses received. This movement is clockwise. When the armature 27 is attracted the toe 45 is out of the path of any of the parts carried by the elements 46 or 49. The pin 44 however is in the path of the element 50 under this condition of things. Assume now that the escapement wheel 37 has been stepped around very nearly 360 degrees so that the finger 50 comes into contact with the pin 44, then the arm 51 is in the path of the arm 43 which thereupon prevents movement of the armature 22, thus preventing any further actuation of the escapement wheel 37. The object of this is that it is also desired to send a number of impulses greater than those required to restore all of the escapement wheels to normal so as to pick up any that may have lagged in the course of the operation of the system. As soon as the impulses cease, the armature 27 moves back into the position shown in Fig. 2, whereupon the toe 45 engages the inclined surface (as shown more clearly in Fig. 11) of the finger 52 and moves the escapement wheel, together with the stud and the parts it carries from the position of Fig. 4 into the position of Fig. 3. The device is then ready for further impulses. Assume now that it is desired to call a station, then impulses are sent sufficient to bring the notch 47 of the selector of such station into alignment with the toe 45. If the impulses then cease the toe 45 falls into the notch at that particular station, and causes engagement between the contact elements 55 and 57 to ring the substation bell at that particular station. As has already been explained the next succeeding station would require two complete cycles of alternating current in order to bring its notch 47 into alignment with the toe 45.

Assume however, that after the station just referred to has been called, that it is desired to lock out all of the remaining stations, then a further cycle of current is sent after the elapse of a certain time interval and this cycle of current causes the re-attraction of the armature 27 and the rotation of the disc 46 so that the projection 48 is now aligned with the toe 45. Upon cessation of these impulses (which as stated 65 are not sufficient to select the succeeding

station) the restoration of the armature 27 to the position shown in Fig. 7 causes the toe 45 to impinge against the projection 48. Under this condition of things no contact is established between the elements 54 and 56. At all of the other stations, however, the toe 45 rests upon the rim of the disc 46 as shown in Fig. 8, and a connection is established between the elements 54 and 56. The establishment of this connection at all 70 of the stations other than the one called short circuits or otherwise renders inoperative part of the substation equipment so that the similar part of only the substation equipment of the station called remains intact 75 for operative purposes. It will be understood, of course, that no station has its local signal operated except that one at which the toe 45 of the element 28 has entered the notch 47. 80

Should it be desired to have all of the substation equipments connected to the line, then the operations of the substation selectors are continued back to their zero position, as shown in Fig. 3, at which time the toes 45 of the elements 28 instead of resting against the periphery of the disc 46 rest against the flat portions 59 of the fingers 52, thus preventing contact between the elements 54 and 56. When no lock out facilities are desired, the required number of impulses are sent to align the slot 47 of the selected station with the toe 45, whereupon the impulses cease, permitting the armature 27 to be retracted to operate the local signal 90 by connecting the elements 55 and 57. Thereupon a surplus of impulses are transmitted over the line until all of the selectors are in the position shown in Fig. 4, whereupon the impulses cease and the restoration 100 of the armature 27 causes the selectors to occupy the position of Fig. 3. All stations are then connected to the line, but only the selected station has been called by having its signal operated. This is of advantage 110 in that it does not deny the use of the line for special or emergency use without again operating the selectors when no privacy is required for the conversation to the called or selected station. 115

Fig. 7 shows the relative position of the elements 28 and 56 when the toe 45 rides upon the projection 48.

Fig. 8 shows the relative position of these elements when the toe 45 rests against the 120 periphery of the disc 46.

Fig. 9 shows the relative position of these parts when the toe 45 rests against the flat surface 59.

The circuit connections are more clearly 125 apparent from Fig. 10 in that I show the substation signal 60 co-operating with a battery 61 and under the control of the elements 55 and 57, as already explained. A substation talking set is shown at 62 and the re- 130

ceiver 63 thereof is shown as having its circuit short circuited by the elements 54 and 56 through the agency of the conductors 64 and 65, whenever said elements 54 and 56 are 5 in electrical engagement. The receiver 63 may of course be of not too high resistance, its associated induction coil being high wound so that this short circuiting does not seriously influence the line conductors. Any 10 other manner of rendering the substation circuit unfit for use may of course be utilized, as will be readily apparent.

From what has been thus described the nature of my invention will be readily clear 15 to those skilled in the art. The angular movement of the disc 46 so as to bring the projection 48 into alignment with the toe 45 instead of the slot 47 requires an impulse or set of impulses not sufficient to place the 20 next succeeding station into condition for receiving a call.

By the very simple arrangement thus outlined I am enabled to provide a lock out system by virtue of which only the called station 25 is in condition to fully respond with its substation equipment. Of course, the short circuiting of the receiver 63 would naturally still leave the transmitter 66 in condition to permit the giving of an emergency 30 call should some station other than the one using the line be desirous of obtaining the line for emergency purposes. Whenever the toe 45 has dropped into a notch 47, then the contact 54 has passed beyond the 35 spring 56 so that at that time no contact is established between the two, although this of course has no special significance.

Having thus described one form which my 40 invention may take, what I claim as new and desire to secure by Letters Patent is:

1. The combination of a plurality of step by step signal receiving devices, each comprising a member having a step by step movement, each of said members being adjustable to occupy any one of a plurality of potential sub-station calling positions, the sub-station calling positions of each of said members being different from that of all the others, means for moving each of said members to its sub-station calling position, a 45 switching device, signal means controlled by said switching device, said switching device comprising a movably mounted element engaging said member having the step by step movement to hold said movably mounted element in signal operating position when the member having the step by step movement with which it is associated is in its sub-station calling position, additional sub-station equipment comprising a receiving device, means for controlling said additional equipment comprising said member, means controlled by said member and operatively actuatable upon actuation of said 50 member to an intermediate position other

than any of said sub-station calling positions whereby said sub-station equipment is maintained in operative position after actuation of said signal, and means whereby said additional sub-station equipment is placed 70 in operative position when said step by step member is in its potential sub-station calling position.

2. The combination of a plurality of step by step signal receiving devices, each comprising a member having a step by step movement, each of said members being adjustable to occupy any one of a plurality of potential sub-station calling positions, the sub-station calling positions of each of said members being different from that of all the others, means for moving each of said members to its sub-station calling position, a switching device, signal means controlled by said switching device, said switching device comprising a movably mounted element engaging said member having the step by step movement to hold said movably mounted element in signal operating position when the member having the step by step movement with which it is associated is in its sub-station calling position, additional sub-station equipment comprising a receiving device, means for controlling said additional equipment comprising said member, means controlled by said member and operatively actuatable upon actuation of said member to an intermediate position other than any of said sub-station calling positions, whereby said sub-station equipment is maintained in 80 operative position after actuation of said signal, and means whereby said additional sub-station equipment is placed in operative position at all said sub-stations when all said step by step members are in their potential 90 sub-station calling or zero position.

3. A device of the character described comprising a sub-station signal receiving member having a step by step movement, additional sub-station equipment, the movement of said member being one of step by step rotation from a starting or zero position to a sub-station calling position, a position for maintaining said additional sub-station equipment in operative condition 110 and again to said starting or zero position, a tiltable member having means thereon engaging said member having said step by step movement, said tiltable member being provided with means for controlling contacts for throwing said additional equipment into and out of operation, and means on said member having said step by step movement engaging said tiltable member to move said last mentioned member into position to maintain said additional sub-station equipment in operative position.

4. A device of the character described comprising a sub-station signal receiving member having a step by step movement.

additional sub-station equipment, the movement of said member being one of step by step rotation from a starting or zero position to a sub-station calling position, a position 5 for maintaining said additional sub-station equipment in operative condition and again to said starting or zero position, a tiltable member having means thereon engaging said member having said step by 10 step movement, said tiltable member being provided with means for controlling contacts for throwing said additional equipment into and out of operation, means on said member having said step by step movement 15 engaging said tiltable member to move

said last mentioned member into position to maintain said additional sub-station equipment in operative position, and means associated with said step by step member engaging said tiltable member to move the same 20 into position to maintain said additional sub-station equipment in operative position when said step by step member reaches its zero position.

In witness whereof, I hereunto subscribe 25 my name this 28th day of June, A. D. 1917.

PAUL GNIFKE.
